UNITED STATES PATENT OFFICE.

LOUIS ROESSEL, OF BROOKLYN, NEW YORK; ARTHUR E. BELLIS, OF SPRINGFIELD, MASSACHUSETTS, AND CHARLES S. COLLINS, OF BRONX, NEW YORK, ASSIGNEES TO BELLIS HEAT TREATING COMPANY, OF NEW HAVEN, CONNECTICUT, A CORPORATION OF CONNECTICUT.

FURNACE.

Application filed May 4, 1921. Serial No. 466,780.

To all whom it may concern:

Be it known that we, LOUIS ROESSEL, a citizen of the United States, and a resident of Brooklyn, in the county of Kings and 5 State of New York, ARTHUR E. BELLIS, a citizen of the United States, and a resident of Springfield, in the county of Hampden and State of Massachusetts, and CHARLES S. COLLINS, a citizen of the United States, and 10 a resident of Bronx, in the county of Bronx and State of New York, have invented new and useful Improvements in Furnaces, of which the following is a specification.

This invention relates to furnaces and 15 more particularly to furnaces of that general type which are used in the heat treatment of metals.

Generically considered, our present invention comprehends the provision of a multiple type furnace designed for the purpose of most efficiently and economically utilizing the generated heat in the treatment of metals or metal alloys in liquid baths.

More particularly, in one embodiment of 25 the invention, we provide a battery of furnace chambers which may be produced in the form of one unitary structure, or may consist of several independent furnace structures together with means for supplying a 30 reducing atmosphere for the high temperature treatment of the metal or metal alloy to one of the furnace chambers and means for conducting the high temperature gases to either one or all of the other furnace 35 chambers for the treatment of the metal or metal alloy at relatively lower temperatures.

In general it is our aim and purpose to provide a multiple furnace structure of the 40 above character which may be advantageously employed for first pre-heating the metal object, then subjecting the same to a high temperature heat treatment, and subsequently quenching the metal object to the desired temperature, the temperatures in the 45 several furnace chambers being under the instant control of the operator thereby resulting in the production of a product of the highest quality with comparatively small consumption of fuel.

50 With the above and other objects in view, our invention consists in the improved form, construction and relative arrangement of the

several parts of the furnace structure to be hereinafter described, illustrated in the accompanying drawing and subsequently incorporated in the subjoined claims.

In the drawings wherein we have illustrated one desirable and practical embodiment of our invention and in which similar reference characters designate correspond- 60 ing parts throughout the several views—

Figure 1 is a longitudinal sectional view through a multiple chambered furnace structure disclosing a preferable embodiment of the invention.

Figure 2 is a top plan view.

Figure 3 is a transverse section taken on the line 3—3 of Figure 2.

In the present art of heat treating high speed steels, it is the usual practice to first 70 heat the steel object in a pre-heating oven type of furnace and then to transfer the object to a high temperature oven type furnace where it is heated to a temperature of 2100 degrees F. to 2200 degrees F., as may be 75 required owing to the composition of the particular metal alloy. The metal piece or object after being subjected to the high temperature heat treatment is then suddenly quenched in an alloy bath at ordinary room 80 temperature, the piece is finally drawn in a lead bath to about 1100 degrees F. This practice is sometimes modified by first pre-heating in an oven type furnace, then heating the piece to the required high tempera- 85 ture in a bath of barium chloride, and then quenching and drawing in an oil bath as above referred to.

A further development in the present art is to pre-heat the metal piece in an oven type 90 furnace and then subject the piece to the required high temperature treatment in a high temperature oven type furnace, then quench in a lead bath at about 1100 degrees F., and finally subquench in oil. This high tempera- 95 ture quench of the metal piece renders unnecessary the drawing operation after the quench.

In the operation and use of our new furnace structure for the high temperature heat 100 treatment of metals, it is our practice to employ either one high temperature bath consisting of fused salts, preferably of eutectic proportions as described in the pending ap-

5 plication of Arthur E. Bellis filed September 24, 1920, Serial No. 412,588, and one
10 quench bath also consisting of an eutectic
mixture of fused salts likewise referred to
in said pending application, or on the other
hand to use a pre-heating bath likewise con-
sisting of an eutectic mixture of fused salts,
a high temperature bath of fused salts and a
quench bath of fused salts, each of the said
15 salt baths having the characteristics of an
eutectic as described in the said Bellis ap-
plication.

In order to obviate distress or physical
15 deterioration of the metal pots or con-
tainers for the salt baths, and more partic-
ularly those used in the high temperature
chamber of the furnace, we employ the
special crucible construction of Patent No.
20 1,358,816 granted to Arthur E. Bellis,
November 16th, 1920, and the protecting or
sealing rings as shown and described in the
pending application of Charles S. Collins,
Serial No. 406,870, filed August 30th, 1920.

Referring now in detail to the accom-
25 panying drawings 5 designates the body of
the furnace structure which may be of fire
brick, masonry or other more or less re-
fractory material, said body structure being
reinforced and supported by the metallic
30 frame work 6 and mounted upon a plurality
of pedestals or supports 7. In the present
illustrated embodiment of our invention we
have shown this furnace structure as pro-
vided with 3 chambers, namely, a pre-heat-
35 ing chamber 8, a high temperature chamber
9 and the quench chamber 10.

These chambers may be of any desired size
and shape. Each chamber opens through
40 the top of the furnace and through such
opening the bath containing pot or crucible
generally indicated at 11 may be inserted.
Preferably the pot which is arranged in the
high temperature chamber 9 is provided
45 with an exterior wall 12 which is more or
less resistant to oxidizing atmospheres and
serves as a protection for the inner liner or
metal pot proper, in accordance with the
patented Bellis crucible construction pre-
viously referred to.

50 A suitably proportioned mixture of air
and gas is supplied to the high temperature
chamber 9 through the medium of the burn-
ers 13. In the present disclosure we have
shown three of these burners arranged in
55 opposite sides of the furnace structure and
delivering the mixture of air and gas into
the chamber at opposite sides of the crucible
arranged therein. An opening indicated at
14 is formed through one side of the furnace
60 structure through which a lighted taper may be
inserted for the purpose of igniting the
gaseous mixture issuing from the burners.

Auxiliary burners 15 and 16 respectively
15 are provided for the preheating and quench-
ing chambers of the furnace structure, and

the lighting openings 17 and 18 respectively
communicate with these chambers through
which the taper may be inserted for igniting
the gas. However, as will be herein-
70 after explained these auxiliary burners are
not used except upon the start of operations
or when it is desired to increase the temper-
atures in these chambers.

The furnace structure 5 is provided with
the passages 19 and 20 respectively which
75 connect the central high temperature cham-
ber 9 with the chambers 8 and 10, said
passages being located at the lower ends of
the furnace chambers. The outlet flues or
80 passages 21 and 22 respectively extends up-
wardly through the furnace structure from
the passages 19 and 20 and open through
the top of the furnace. The upper ends
85 of these outlet flues may be closed by means
of suitable plates or closures. Additional
outlet passages 23 and 24 respectively con-
nect with the upper ends of the preheating
and quench chambers 8 and 10 and open
through the top of the furnace structure.
90 Suitable dampers indicated at 25 are pro-
vided for the purpose of controlling the
passage of the products of combustion from
the central preheating chamber 9 into the
passages 19 and 20, thus enabling all of
95 these products to be passed into either one
of the chambers 8 or 10 or to be equally dis-
tributed to said chambers.

The furnace structure is further provided
with drainage openings 26 communicating
100 with the lower end of each of the chambers
through which any overflow from the cruci-
bles may be drained off.

In the operation of our improved multi-
105 ple type furnace as above described, the salt
bath solution contained in the crucible in
the central chamber 9 of the furnace is
maintained at a temperature of from 2000
to 2300 degrees F., as may be required by
110 the particular work in hand. This tem-
perature of the bath solution necessitates a
combustion chamber temperature of about
2500 to 2700 degrees F., and the products
of combustion leaving this chamber are
115 usually above 2200 degrees F. If these gases
were allowed to escape to the atmosphere
without utilizing the heat energy contained
therein, a great waste of fuel would result.
However, by means of our improved furnace
120 structure, we conduct these high temperature
waste gases from the central chamber 9 to
the preheating chamber 8 and the quench
chamber 10. We have found in practice
that there is sufficient heat contained in these
125 waste gases to maintain the required tem-
perature of the preheating bath solution,
namely, approximately 1600 degrees F., and
likewise the required temperature of the
quench bath solution, namely, approximate-
ly 1300 degrees F. These temperatures in
130 the preheating and quenching baths may be

attained at the start of operations by using the auxiliary burners 15 and 16 respectively or if at any time it is desired to increase these temperatures then the auxiliary burners are employed. The temperatures in the pre-heating and quench chambers can also be varied and controlled by the proper manipulation of the dampers 25.

As is well known, a metallic pot or crucible when subjected to high temperatures in a heating chamber containing an oxidizing atmosphere, very rapidly deteriorates due to oxidization. It is therefore evident that if a constant reducing atmosphere is maintained in the combustion chamber, the oxidization of the metal pot will be decreased. In present practice in this art, the fuel is frequently burned with an excess of air. The products of combustion containing free oxygen therefore unite with the metal of the pot and cause sealing. Furnaces as now used in the high temperature treatment of metals are provided with vents at the top of the furnace chamber so that free air can pass through the furnace, such air entering at the burner openings at the bottom of the furnace chamber. This free atmospheric air in its passage through the chamber causes rapid oxidization and scaling of the pot wall after the fuel has been turned off and while the pot and its contents are cooling.

In the operation of our new furnace construction we fire the central high temperature chamber in the upper area and the waste gases are passed to the end chambers and then out to the atmosphere at the top of these end chambers. It will therefore be manifest that there is no draft effect through this central chamber to cause atmospheric air to enter the furnace when the fuel supply is cut off. In order to control and maintain a reducing atmosphere in the furnace chamber, we employ a system which produces a constant ratio of air to gas irrespective of the rate of flow, and adjust the system so as to provide a reducing atmosphere. Our preferred embodiment of such a system of firing is fully shown and described in Letters Patent 1,290,513 granted January 17, 1919, to Charles S. Collins and Louis Roessel. The adaptation of this proportional regulating system for the air and gas flow to our improved furnace structure will be readily perceived upon a perusal of the said patent.

From the foregoing description considered in connection with the accompanying drawings, the construction, manner of operation and several advantages of our improved multiple type furnace will be clearly understood. We have successfully demonstrated in practice that such a furnace construction results in great economy in the high temperature heat treatment of

metals, first by the appreciable reduction in fuel consumption due to the fact that a great part of the heat in the gases leaving the high temperature chamber is utilized for heating the lower temperature pre-heating and quench bath chambers, and secondly, by prolonging the life of the pots or crucibles which are used in connection with the furnace. The maintenance of proper temperatures in the three furnace chambers is always under the control of the operator by the simple manipulation of the fuel flow regulating valves and the adjustment of the waste gas control dampers.

In the foregoing description we have set forth in detail the several structural features of a multiple type furnace which we have found to give highly satisfactory results. Nevertheless, it is to be understood that this invention might also be exemplified in numerous other furnace structures. Thus for instance, instead of producing the furnace in the form of a single unitary structure with the series of chambers, we might provide separate and distinct furnaces each having a single chamber, more or less widely separated from each other and connected by suitable pipes or conduits constituting the equivalent of the waste heat conducting passages or flues. Further, as will be readily apparent to one skilled in the art the several detail parts of the improved furnace might be variously changed or modified, and we therefore reserve the privilege of resorting to all such legitimate alterations in the form, proportion and relative arrangement of the several elements of the described construction as may be fairly embodied within the spirit and scope of the invention as claimed.

We claim:

1. A furnace for heat treating metals having a high temperature chamber from which free air is excluded, and preheating and quench chambers open to the atmosphere, means for supplying a combustible fuel mixture to the high temperature chamber, and means for transferring the products of combustion from said high temperature chamber to the preheating and quench chambers.

2. In the heat treatment of metals, a high temperature furnace chamber and preheating and quench chambers, each of said chambers adapted to receive a crucible containing a fused salt treatment bath, means of affording communication between the several chambers at their lower ends, and means for supplying a combustible fuel mixture to the high temperature chamber, the products of combustion being conveyed from said chamber through the communicating means to the preheating and quench chambers.

3. In the heat treatment of metals, a fur-

- 4
 nace structure having a high temperature chamber and preheating and quench chambers, each of said chambers adapted to receive a crucible containing a heat treatment 5 bath, said furnace structure having passages connecting the several chambers to each other at their lower ends, said high temperature chamber being closed to the atmosphere and the preheating chamber and quench 10 chambers having vent openings at their upper ends and a plurality of fuel burners for the high temperature chamber, the products of combustion being conducted by said passages to the preheating and quench 15 chambers.
4. In the heat treatment of metals, a furnace structure having a high temperature chamber and preheating and quench chambers, each of said chambers adapted to receive a crucible containing a heat treatment 20 bath, said furnace structure having passages connecting the several chambers to each other at their lower ends, said high temperature chamber being closed to the atmosphere 25 and the preheating chamber and quench chambers having vent openings at their upper ends, a plurality of fuel burners for the high temperature chamber, the products of combustion being conducted by said passages to the preheating and quench chambers and auxiliary burners for the preheating and quench chambers.
5. In the heat treatment of metals, a furnace structure having spaced chambers each 35 adapted to receive a crucible containing a bath solution and a passage connecting said chambers to each other at their lower ends, one of said chambers being closed to the exterior air and the other of said chambers 40 having a vent opening at its upper end, and a plurality of fuel burners for the first named chamber arranged above said connecting passage to heat the contents of the crucible to a high temperature, the products 45 of combustion being conducted by said passage from said high temperature chamber to the other of the chambers to heat the contents of the crucible therein to a relatively lower temperature.
6. In the heat treatment of metals, a furnace structure having spaced chambers each adapted to receive a crucible containing a bath solution and a passage connecting said chambers below the crucibles to each other 55 at their lower ends, one of said chambers being closed to the exterior air and the other of said chambers having a vent opening at its upper end, a plurality of fuel burners for the first named chamber to heat the contents of the crucible to a high temperature, the products of combustion being conducted by said passage from said high temperature chamber to the other of the chambers to heat the contents of the crucible therein to a relatively lower temperature, and means for 60 controlling the passage of the products of combustion between said chambers.
7. In the heat treatment of metals, a furnace structure having spaced chambers each adapted to receive a crucible containing a treatment bath and a passage connecting said chambers at their lower ends, the furnace structure being further provided with an outlet flue communicating with said passage, one of said chambers being closed to the exterior air and the other chamber having a vent opening at its upper end, and a plurality of fuel burners for the first named chamber to heat the contents of the crucible 70 therein to a high temperature, the products of combustion being conducted from said high temperature chamber to the other of said chambers to heat the contents of the crucible 75 therein to a relatively lower temperature.
8. In the heat treatment of metals, a furnace structure having a high temperature chamber and preheating and quench chambers, each of said chambers adapted to receive a crucible containing a treatment bath, 80 said furnace structure provided with passages connecting said chambers to each other at their lower ends, the high temperature chamber being closed to the exterior air and the preheating and quench chambers having vent openings at their upper ends, a plurality of primary burners for the high 85 temperature chamber, auxiliary burners for the preheating and quench chambers, the products of combustion being conducted by said passages from the high temperature chamber to the preheating and quench chambers, and means for controlling the distribution of the products of combustion to the latter chambers.
9. In the heat treatment of metals, a furnace structure having a high temperature chamber and preheating and quench chambers, each of said chambers adapted to receive a crucible containing a treatment bath, 90 said furnace structure provided with passages connecting said chambers to each other at their lower ends, the high temperature chamber being closed to the exterior air and the preheating and quench chambers having vent openings at their upper ends, a plurality of primary burners for the high 95 temperature chamber, auxiliary burners for the preheating and quench chambers, the products of combustion being conducted by said passages from the high temperature chamber to the preheating and quench chambers, and means for controlling the distribution of the products of combustion to the latter chambers.
10. In the art of heat treating metals by means of a plurality of fused salt solutions maintained at relatively different tempera- 100 105 110 115 120 125 130

tures; the method which consists in heating the high temperature bath solution containing crucible in a reducing atmosphere to the requisite temperature and utilizing the 5 exhausted heating medium for heating the crucibles containing the relatively low temperature bath solutions.

In testimony that we claim the foregoing as our invention, and we have signed our names hereunder.

LOUIS ROESSEL.
